UNITED STATES PATENT OFFICE.

CHARLES S. BATDORF, OF BROOKLYN, NEW YORK.

MOVING-PICTURE APPARATUS.

1,023,797.

Specification of Letters Patent. Patented Apr. 23, 1912.

Application filed December 15, 1910. Serial No. 597,558.

To all whom it may concern:

Be it known that I, CHARLES S. BATDORF, a citizen of the United States, and a resident of Brooklyn, in the county of Kings and State of New York, have invented certain new and useful Improvements in Moving-Picture Apparatus, of which the following is a specification.

The invention relates to improvements in moving picture apparatus of the class employing, preferably, a long film, and it consists in the novel features, structure and arrangement of parts hereinafter described and claimed, applicable alike to cameras for photographing objects in motion and for projecting machines by which the pictures taken with the use of the camera are thrown upon a screen or exhibited.

The invention is presented in this application as embodied in a camera employing a shutter, a photographic lens, and a film of usual character intended by intermittent movements to be carried across the path of the lens and receive the successive impressions or images in accordance with existing methods.

The novelty of my invention resides in the provision of special means for mounting and effecting the travel of the film and arranging the same absolutely and positively at fixed predetermined periods, the shutter being away from the path of the lens during the periods the film is at rest and closing said path during the periods that the film is in motion.

It is too well known to require special explanation that in moving picture apparatus as heretofore constructed, the cameras are defective in respect of being able to take photographs of objects in rapid motion with the extreme accuracy, uniformity of sequence and rapidity requisite to meet the wants of this art, and it is equally well known that hundreds of attempts have been made to remedy the existing objections to this class of apparatus. The chief difficulty in both cameras and projecting machines has arisen in the means employed for moving and controlling the film. In many instances inventors have followed the plan of providing means of various kinds, such as prongs and the like, for engaging successive intermediate sections of the film and pushing the same across the path of the lens and while these machines have operated with more or less success, it has long been

obvious that the art requires and deserves higher development. The character of the final result depends greatly on the precision of movements and control of the film, and the purpose of my invention is to provide simple and effective means for with extreme accuracy and reliability effecting the proper movements and control of the film in cameras and projecting machines.

I deem it to be one of the greatest objections to existing cameras using a tape-film that successive intermediate sections of the film are positively engaged by power driven means, manually or otherwise actuated, and pushed thereby across the path or plane of the lens. The effect of the action of the mechanisms engaging successive intermediate portions of the film and moving the same across the lens is readily observable in moving picture exhibitions, the display while in many instances entertaining, not depicting the scene with that faithfulness, smoothness and consistency which should be attained.

In accordance with my invention, one of whose purposes is to simplify moving-picture apparatus, I keep the entire film under control both during the periods of movement and periods of rest, I effect all the movements of the film from power applied to one end thereof, which is a feature of advantage, and I secure the film positively and uniformly in its periods of rest by an escapement mechanism which will engage and hold the film at precise predetermined intervals of its length and for precise predetermined periods of time, the motive power or the driving shaft continuing in movement without interruption during the at-rest periods of the film and acting to keep a tension on the film sufficient for the control of the latter but insufficient to tear the film from the escapement mechanism.

In carrying out my invention I have produced a substantially noiseless mechanism avoiding the clicking noises so common to cameras and projecting machines in this art.

The invention will be fully understood from the detailed description hereinafter presented, reference being had to the accompanying drawings, in which:

Figure 1 is a vertical longitudinal section through a camera constructed in accordance with and embodying the invention, the section being on the dotted line 1—1 of Fig. 4; Fig. 2 is a detached transverse sectional view of a portion of the camera showing more

particularly the take-up roll and the friction clutch therefor; Fig. 3 is a detached sectional view, on a reduced scale, of a portion of the camera taken on the dotted line 3—3 of Fig. 4; Fig. 4 is a horizontal longitudinal section, partly broken away, through the camera, on the dotted line 4—4 of Fig. 1; Fig. 5 is an enlarged section of the escapement mechanism of the camera taken on the dotted line 5—5 of Fig. 4; Figs. 6 and 7 are enlarged corresponding views of the escapement mechanism representing the two different positions of a lever portion thereof; Fig. 8 illustrates a modification of the invention in which the lever of the escapement mechanism is arranged to directly engage the film in lieu of an intermediate sprocket wheel or part itself engaging the film, Fig. 8 being a detached side elevation, partly in section, of a portion of the camera; Fig. 9 is a horizontal section through a portion of the camera equipped with the modified escapement mechanism shown in Fig. 8; Fig. 10 is a vertical longitudinal section through a camera equipped with the escapement mechanism shown in Figs. 8 and 9; and Fig. 11 is a detached view of a piece of a film possessing elongated apertures in its opposite edges to be engaged by the parts of the escapement mechanism shown in Figs. 8, 9 and 10.

I will first describe the invention as presented in Figs. 1 to 7 inclusive, and then the modified form thereof shown in Figs. 8 to 11 inclusive.

Referring to Figs. 1 to 7 of the drawings, 15 designates the box or casing having the usual or any suitable lens holding frame 16 and shutter 17. Within the box 15 I mount upper and lower horizontal transverse shafts 18, 19, both preferably being on the same vertical plane, on which I mount, respectively, the let-off reel or drum 20 and take-up reel or drum 21 for the film 22, 40 which is of the usual character having in its opposite edges evenly spaced holes, my invention not necessarily requiring any change in the films commonly employed in this art. Primarily the film is fastened at 45 one end to the hub of the reel 20 and closely wound thereon, and thereafter the other end of the film is drawn over the guide-rolls 23, 24 and fastened to the hub of the reel 21 preparatory to the film being wound on said 50 hub during the rotation of the reel 21 to move the film across the line of the lens. The rolls 23, 24 are on the same vertical plane and between them is a suitable film-guide 25 through which the film passes and, 55 which is open at its center. The reel 20 is equipped with a friction-brake 26 to prevent its rotation except under a sufficient pull on the film by the reel 21 to overcome the force of said brake. The reel 21 is rotated 60 by a cord 27 and friction-pulley 28 (Fig.

2) which is held against the end of the reel 21 by means of a spring 29 whose tension may be adjusted by a nut 30. The cord 27 and pulley 28 may effect the rotation of the reel 21 and the winding thereon of the film 22 except when said film is held against traveling movement by the mechanism of my invention and at its at-rest periods, at which times the cord 27 and wheel 28 will continue in movement but the reel 21 will remain stationary, the wheel 28 slipping frictionally against said reel and by its tendency to rotate the same causing the reel to maintain a tension on the film, whereby the latter is kept properly taut. The cord 27 passes over a pulley 31 secured on the power or driving shaft 32, which in the present instance is equipped with a crank 33 (Fig. 4) for manual operation. It is obvious that any suitable means may be employed for driving the shaft 32, which when the camera is in use will have a continuous rotation. In rear of the film-guide 25 is mounted a horizontal transverse shaft 34 upon which are loosely mounted suitably spaced-apart sprocket wheels 35, 36 whose teeth or peripheral projections are definitely arranged to regularly enter the edge holes in the film 22 as the latter travels toward the reel 21, said teeth or projections and consequently the wheels 35, 36 always remaining in engagement with the film. When the film 22 is traveling, during its intermittent movements, it effects by its engagement therewith the rotation of the wheels 35, 36, said wheels having no movement whatever except that imparted to them by the film, and when it is necessary that the film remain at rest, as during exposures, the wheels 35, 36 are, in accordance with my invention, held stationary and by their engagement with the film hold it stationary. The wheels 35, 36 are made rotatable merely that they may maintain a constant engagement with the film and they at no time have any effect to cause the film to travel, their function being to hold the film, at the proper times, stationary. In order that the film may have no possible reverse movement or action at the moments of its respective successive stoppages which might possibly happen due to the suddenness with which the film is arrested, I provide on the wheel 35 a smooth annular rim 37 (Figs. 3 and 4) to be engaged by a ball-brake 38 of known character adapted to permit the wheel 35 to rotate in one direction with the moving film and prevent any reverse rotation of the wheel and consequently any reverse movement of the film. The wheels 35, 36 are held stationary, to thus hold the film, at predetermined uniform intervals by mechanism comprising a series of equally spaced-apart laterally projecting pins 39 on said wheels, slideable bars 40

40 having laterally extending stop-plates or flanges 41, and bell-crank levers or members 42 pivotally secured to said bars 40 and comprising arms 43 to be engaged by the successive pins 39 and moved thereby into engagement with the stops 41, arms 44 connected with springs 45 normally under tension to initially hold the forward ends of the arms 43 depressed (Figs. 1, 5, 6) and forks composed of fingers 46, 47 loosely straddling stops or lugs 48 rigid on the slidable bars 40, the fingers 46 engaging the stops 48 in one position of the bell-crank members 42 to arrest the same thereat, as shown in Fig. 6, and the fingers 47 preferably engaging said stops in the other position of said members 42, as shown in Fig. 7. The fingers 47 might be omitted altogether, since when they engage the stops 48 the arms 43 engage the flanges 41 but a more durable construction is presented when the fingers 47 are provided. The bars 40 at their forward ends have slots 49 through which the shaft 34 passes and which enable the shaft to support the said ends of said bars and limit their forward and backward sliding movements. The rear ends of the bars 40 are secured on a transverse horizontal slidable rod 50 whose ends are mounted in guides 151 (Fig. 4) secured to the sides of the box or casing 15. The rod 50 slides back and forth with the bars 40 and imparts sliding movement thereto, said rod 50 being connected by a link 51 and crank 52 with the shaft 32, whose rotation causes said crank and link to uniformly effect a forwardly and backwardly sliding movement of the rod 50 and bars 40 with the parts hereinbefore enumerated carried by said bars. When the bars 40 are in their forward position and while moving rearwardly therefrom with the bell-crank members 43 in their initial position shown in Fig. 6, the reel 21 may during its rotation effect the travel of a predetermined length of the film, previously exposed to receive an impression or image, from the line of the lens and during this travel of the film it will rotate the wheels 35, 36 and cause corresponding pins 39 thereof to pass upwardly against the forward ends of the bell-crank members 43 then in the path of said pins, as represented in Figs. 5 and 6, and move said members upwardly in opposition to the force of the springs 45 until said members reach and become arrested by the stop flanges 41 and the fingers 47 engage the stops 48, as shown in Fig. 7, and thereupon the wheels 35, 36 will be temporarily locked against further rotation and hold the film absolutely stationary. The wheels 35, 36 remain locked against rotation and hold the film stationary to receive an image until the crank 52, which is in constant motion, draws the link 51, rod 50 and bars 40 rearwardly

from the position said bars are shown in Figs. 6 and 7, and then drives said parts forwardly again. When the crank 52 draws the bars 40 rearwardly the bell-crank members 43 slide rearwardly from the wheel-pins 39 which engaged them (Fig. 7) and turn downwardly under the force of the springs 45 and at the same time the stop-flanges 41 move rearwardly over said pins 39, as shown in Figs. 1 and 5 and continue the holding of the wheels 35, 36 and film 22 stationary, and when the bars 40 are driven forwardly again (the members 43 then being in their lower position) the stop-flanges 41 will pass forwardly from over said pins 39 and release the wheels 35, 36 to rotate and the film 22 to have a further traveling movement, the members 43 at the same time being thrust forwardly in the path of the succeeding pins 39, which will on the rotation of said wheels engage said members and move them upwardly against the flanges or stops 41 as before. The bars 40 constantly slide forwardly and rearwardly, and when they are in their forward position and starting rearwardly, with the bell-crank members 43 inclined downwardly, they permit the rotation of the wheels 35, 36 and the travel of the film until corresponding pins 39 on said wheels move said members 43 upwardly against the stops 41, and they then hold the said wheels and film stationary until the bars move rearwardly (releasing the members 43 from said pins, Fig. 5) and then forwardly again to carry the stops 41 from said pins. The arrest or exposure periods of the film are, thus, during those portions of the rearward movements of the bars 40 that the pins 39 are against the members 43 while the latter are engaged with the stops 41 and against the said stops 41 and during those portions of the forward movements of said bars 40 that said stops 41 remain directly over and engage with said pins. The periods at which the wheels 35, 36 may rotate and the film perform its traveling movement (the shutter 17 then being in its closed position) are during those portions of the forward movements of the bars 40 which take place after the stops 41 leave the pins 39 engaging them and during those portions of the rearward movements of said bars which occur during the time the succeeding pins 39 are moving the bell-crank members 43 upwardly against the stops 41. The pins 39 are carried on the line of a circle toward the bell-crank members 43 and hence may reach and move said members upwardly during the rearward movement of the bars 40 and without requiring any stoppage of said bars. During the forward and backward movement of the bars 40 with pins 39 of the wheels 35, 36 against the upwardly turned lever members 43 and against the

stop flanges 41 when said lever members are in their lower position, the wheels 35, 36 remain stationary and hold the film stationary, as hereinbefore explained, but 5 the crank 33 and pulley wheels 31, 28 may continue in movement, the wheel 28 slipping against the end of the reel 21 and while not rotating the latter causing the same to maintain a tension pull on the film 10 then held stationary by the locked wheels 35, 36. In the use of the camera the crank 33 or other means for driving the shaft 32 may be kept in constant motion, but the film 22 will have uniform intermittent 15 movements, said film being locked at predetermined intervals against movement by the locking of the wheels 35, 36 by means of the parts connected with the sliding bars 40. In constructing the camera due 20 regard must be had to the spacing of the pins 39 on the sprocket wheels 35, 36 and the length and location of the lever members 43 and stop flanges 41 so that the intervals of movement of the film may be of 25 the predetermined desired extent. I regard the sliding bars 40 with their members 42, 41 and the sprocket wheels 35, 36, having the pins 39 as an escapement mechanism, and this mechanism is of the most 30 reliable character in effecting the proper, accurate, predetermined periods the successive sections of the film shall remain at rest. The shutter 17 is the ordinary rotary shutter employed in moving picture 35 machines, and it may receive its rotary motion from the driving shaft 32 through beveled gear wheels 53 and auxiliary shaft 54. The shutter 17 is employed in my camera for identically the same purposes it is used to 40 accomplish in other cameras. The guide 25 will preferably be formed from sheet metal and secured upon a rod 55 extending transversely across the casing 15 and provided on one end with a crank 56 by which 45 the rod may have a partial rotary movement imparted to it for swinging the guide 25 forwardly from the immediate vicinity of the sprocket wheels 35, 36 when it is desired to free the film from said wheels and 50 also when it is desired to apply the film strung through said guide, to said wheels. The crank 56 is formed with a hinged part 57 carrying a pin 58 adapted to enter a recess provided for it in the casing 15, as 55 shown in Fig. 4, whereby to hold the rod 55 stationary. The section 57 of the crank is hinged so as to enable a ready detachment of the pin 58 from its engagement with the recess in the casing 15. A spring 59 60 carried by a rigid portion of the crank 56 normally exerts a pressure against the hinged member 57 tending to press the pin 58 against the casing 15. The spring 59 serves to detachably lock the pin 58 in its recess in the side of the casing 15.

My invention is not limited to the details of any special mechanism constituting the escapement for effecting the successive stoppages of the film, and in Figs. 8, 9 and 10 I illustrate a modified form of escapement 70 mechanism which is entirely reliable and adapted to engage the film without the employment of the sprocket wheels 35, 36. In the construction shown in Figs. 8, 9 and 10 I employ, for each edge of the film, a slide- 75 able bar 60 having a rearwardly projecting finger 61 and carrying a bell-crank member 62 which affords a forwardly projecting finger 63 to coöperate with the finger 61 in controlling the film, which in this modifica- 80 tion I number 64. The bell-crank member 62 is pivotally mounted on a bearing 65 and has its short arm connected with the bar 60 by means of a coiled spring 66 whose tension is normally exerted to turn the finger 63 up- 85 wardly to the limit permitted by the shoulders 67, 68, respectively, on the member 62 and bearing 65. The film 64 is formed in its opposite edges with elongated openings 69, as shown in Fig. 11, and these openings at 90 each edge of the film are utilized in connection with the fingers 61, 63 in controlling the intermittent movements of the film. The finger 61 is rigid on the bar 60 and the finger 63 may have a pivotal movement on 95 the bearing 65. In the position of the parts shown in Fig. 8 it may be understood that the bar 60 is on its forward movement and that the film is being pulled downwardly by the take-up reel. It will be observed that 100 the finger 63 during the forward movement of the bar 60 has entered a hole 69 in the film 64. During the downward movement of the film 64, with the parts in the position shown in Fig. 8, the film acting against 105 the finger 63 will turn the latter downwardly until its forward end meets and becomes arrested by the rear end of the finger 61, and thereupon no further downward movement of the finger 63 being permitted, 110 the film 64 will become arrested and remain so during the reverse travel of the bar 60, which will carry the finger 61 into the opening in the film occupied by the finger 63, and until the bar 60 has moved sufficiently 115 forward again to carry the finger 61 from the said opening in the film. When the finger 63 has been moved downwardly against the finger 61 by the film and the bar 60 moves rearwardly to carry the finger 61 into 120 the opening in the film occupied by the finger 63, the finger 63 will be carried rearwardly from the film and the spring 66 will turn said finger upwardly into suitable position to again enter an opening 69 in the film on the succeeding forward movement of the bar 60. The forward movement of the bar 60 operates to retract the finger 61 from the opening in the film and when this 125 happens the finger 63 then in its upwardly 130

turned position will have entered another hole in the film so that during the following downward movement of the film then released by the finger 61, the film may again 5 move the finger 63 downwardly against the rear end of the finger 61 preparatory during the succeeding rearward movement of the bar 60 to the finger 61 passing into the opening in the film which engaged the 10 finger 63 and locking the film against movement until on the succeeding forward movement of the bar 60 the finger 61 is carried from its engagement with the film. The rear end of the finger 61 is beveled down- 15 wardly and rearwardly and the forward end of the finger 63 is correspondingly beveled, and hence during the rearward movement of the bar 60 the rear end of the finger 61 may assuredly enter the opening in the film with 20 the forward end of the finger 63 therein, so as to engage and lock the film, before the finger 63 can spring upwardly therefrom. The beveling of the ends of the fingers 61, 63 is a detail which is carried out, also, in 25 the construction of the escapement mechanism shown in Figs. 6 and 7. I mount the bearings 65 for the bell-crank members 62 on a transverse rod or rock-shaft 70 carried by the bars 60 and upon one end of the rod 30 70 I provide a crank 71 of the construction I have hereinbefore described as being on the end of the rod 55 (Fig. 4). By means of the crank 71 and its parts the rod 70 may be locked in normal stationary relation to 35 the bars 60, as shown in Fig. 8, and by turning the crank downwardly and engaging its pin with the hole 72 in a depending part of the bar 60, the bearings 65 may be swung rearwardly on the arc of a circle and carry 40 the bell-crank levers 62 sufficiently from the fingers 61 to enable both the fingers 61 and 63 to be free of the film 64. When the parts are in their normal operative position shown in Fig. 8, it will be seen that one finger 61 45 or the other finger 63 is always in one of the openings of the film, and hence it is obvious that the film is kept under constant control by means which hold the film in its at rest positions during uniform or unvarying successive periods. The reels 20, 21 of 50 Fig. 1 are employed in the construction shown in Fig. 10, Figs. 1 and 10 differing mainly in the fact that the escapement mechanism of Fig. 10 differs from that 55 shown in Fig. 1 in details of construction, both mechanisms having the same duty to perform which is to effectually and reliably hold the film against movement during successive unvarying periods and to permit the film to have a uniform intermittent movement under a force exerting a pull on one end of the film, such pull keeping the film under control and coöperating with the escapement mechanism in securing in the film 60 that precision of action so necessary in ob-

taining photographs or projecting images faithfully depicting scenes or objects or persons in motion.

What I claim as my invention and desire to secure by Letters Patent, is:

1. An apparatus of the character described comprising a film to be carried by intermittent movements across an exposure opening, let-off and take-up mechanisms for said film, driving means connected with the take-up mechanism for causing the same to exert a pull on the film from the end thereof and effect thereby the travel of the film, and a two-part escapement mechanism connected with the driving mechanism and one 75 part of which is independently movable to its operative position by the film.

2. An apparatus of the character described comprising a film having along its length spaced openings therein, let-off and take-up mechanisms for said film, means connected with the take-up mechanism for causing the same to exert a pull on the film at the end thereof and effect thereby the travel of the film, and escapement mechanism 80 engaging the film at the openings therein to arrest the same at predetermined intervals of its length and for predetermined periods at the exposure opening of the apparatus, said escapement mechanism 85 comprising a stop operable from the driving mechanism and a coöperating independently movable member also connected with the driving mechanism and operable on its movement to its operative position by the 90 film during its movements.

3. An apparatus of the character described comprising a film having along its length spaced openings therein, let-off and take-up mechanisms for said film, means connected with the take-up mechanism for causing the same to exert a pull on the film at the end thereof and effect thereby the travel of the film, and escapement mechanism 105 in constant engagement with the film at successive openings therein for controlling its periods of rest, said escapement mechanism comprising a stop operable from the driving mechanism and a coöperating independently movable member also connected with the driving mechanism and operable on its movement to its operative position by the 110 film during its movements.

4. An apparatus of the character described comprising a film to be carried by intermittent movements across the exposure opening and having therein along its length spaced openings, driving mechanism for drawing the film from one end thereof across said opening, and escapement mechanism operable from said driving mechanism engaging said film at the openings therein for controlling its periods of rest at said opening, said escapement mechanism comprising a stop operable from the driving 120 mechanism 125 130

mechanism and a coöperating independently movable member also connected with the driving mechanism and operable on its movement to its operative position by the 5 film during its movements.

5. An apparatus of the character described comprising a film to be carried by intermittent movements across the exposure opening and having spaced openings therein 10 along its length, driving means connected with one end of said film for drawing the same across said opening, escapement mechanism operable from said driving means engaging said film at the openings therein for 15 arresting the same during its intended periods of rest, and means enabling the drive mechanism to continue in motion during the at-rest periods of the film and maintain a controllable tension thereon, said escapement 20 mechanism comprising a stop operable from the driving mechanism and a coöperating independently movable member also connected with the driving mechanism and operable on its movement to its operative position 25 by the film during its movements.

6. An apparatus of the character described comprising driving mechanism engaging the film at one end for drawing the same across the exposure opening, and a 30 two-part escapement mechanism connected with the driving mechanism and one part of which is independently movable to its operative position by the film.

7. An apparatus of the character described comprising a film to be carried by intermittent movements across an exposure opening and having spaced openings along its length, a let-off reel for said film, a take-up reel for the same and to which one end of 40 the film is secured, driving means connected with the take-up reel for effecting the travel of the film by power exerted at the end thereof, and escapement mechanism operable from the driving means to engage successive 45 openings in the film at a location intermediate said reels for controlling the at-rest periods of the film said escapement mechanism comprising a sprocket wheel constantly engaging the openings in the film

and having spaced-apart stop-pins at the 50 side thereof, a slide carrying a stop and a pivoted spring-pressed member to be engaged by the successive stop-pins and moved thereby against said stop for arresting the wheel and film, and means connecting 55 the slide with the drive-mechanism of the apparatus.

8. An apparatus of the character described comprising a film, a reel on which 60 said film is wound, a rewinding reel to which one end of the film is secured, means for rotating the latter reel, and an escapement mechanism between the reels engaging the openings in the film for arresting the latter at predetermined intervals of its 65 length and for predetermined periods of time, said escapement mechanism comprising a stop operable from the driving mechanism and a coöperating independently 70 movable member also connected with the driving mechanism and operable on its movement to its operative position by the film during its movements.

9. An apparatus of the character described comprising a film, a reel on which 75 said film is wound, a rewinding reel to which one end of the film is secured, means for rotating the rewinding reel and adapted to slip during the at-rest periods of the film without losing control thereof, and an escapement mechanism between the reels 80 engaging the openings in the film for arresting the latter at predetermined intervals of its length and for predetermined periods of time, said escapement mechanism comprising a stop operable from the driving mechanism and a coöperating independently 85 movable member also connected with the driving mechanism and operable on its movement to its operative position by the film 90 during its movements.

Signed at New York city, in the county of New York and State of New York, this 13th day of December A. D. 1910.

CHARLES S. BATDORF.
